[57] CLAIM

The ornamental design for a boat planing inducing attachment for marine outboard motors and marine inboard/outboard power units, as shown and described.

DESCRIPTION

FIG. 1 is a perspective view of a boat planing inducing attachment for marine outboard motors and marine inboard/outboard power units showing my new design, it being understood that the broken lines are for illustrative purposes only;

FIG. 2 is a top plan view thereof;

FIG. 3 is a side elevational view thereof;

FIG. 4 is a front elevational view thereof;

FIG. 5 is a rear elevational view thereof; and

FIG. 6 is a bottom plan view thereof.
